UNITED STATES PATENT OFFICE

HOWARD A. THOMPSON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed August 24, 1928. Serial No. 301,842.

My invention relates to railway traffic controlling apparatus and particularly to apparatus for the control of traffic governing devices, such as railway signals and tripper arm 5 train stops, by current flowing from one track section to another, such sections being included in the same track circuit.

I will describe one form of apparatus embodying my invention, and will then point 10 out the novel features thereof in claims.

In the accompanying drawings, Figs. 1 and 15 2 are views which, when placed end to end with Fig. 1 to the left, constitute a diagrammatic view showing one form of apparatus embodying my invention.

Referring to the drawings, the reference characters 1 and 1^a designate the rails of a stretch of railway track, along which traffic moves from station W toward station Z as indicated by the arrows. Rail 1^a is divided by insulated joints 2, to form a plurality of track sections A—B, B—C, C—D, etc., joints 2 being so located that the entering end I of section H—I is adjacent the departure end of 20 station W, the entering end C of section B—C is adjacent the arrival end of station Z, and the leaving end A of section A—B is adjacent the departure end of station Z.

Sections D—E, E—F, F—H, and H—I are 25 included in one track circuit, which is provided with a track relay designated by the reference character L^I and connected across rails 1 and 1^a adjacent the entering end of section H—I. Current is supplied to this track circuit by a transformer, designated by the reference character 3 and connected through a usual impedance device 4 to rails 1 and 1^a adjacent the leaving end D of section D—E. Sections A—B, B—C, and 30 C—D are included in a second track circuit, which is provided with a second track relay designated by the reference character L^A and connected across rails 1 and 1^a adjacent the leaving end A of section A—B. Current is 35 supplied to this track circuit by a transformer, designated by the reference character 3 and connected through a usual impedance device 4 to rails 1 and 1^a adjacent the entering end D of section C—D. Track relay L^X, 40 shown connected to rails 1 and 1^a adjacent

the right-hand end of section H—I, is controlled by a track circuit comprising 3 sections and extending through station W similarly to the track circuit which controls relay L^A at station Z.

The primary winding of each of the track transformers 3 is continuously supplied with current by line wires α and σ , which are in turn continuously supplied with current by generator X. Track relays L are of a type 55 provided with two windings, 7 and 8, winding 7 being connected to the track rails and winding 8 being continuously supplied with current by line wires α and σ . The adjoining sections within each of the track circuits are 60 connected together through the primary winding of a transformer 5, the secondary winding of which supplies alternating current to a rectifier 6, which supplies direct current for energizing an auxiliary relay 65 designated by the reference character K with a suitable distinguishing exponent. Each rectifier 6 may be made up of a plurality of asymmetric units similar to those disclosed and claimed in Letters Patent of the United 70 States, No. 1,640,335, granted to L. O. Grondahl, August 23, 1927.

Reference character P, with a suitable distinguishing exponent, designates a train controlling device located adjacent points I, F, 80 E, D, and A, respectively. Each of these devices operates a circuit controller designated by the reference character a with a distinguishing exponent, contacts of which are shown in connection with devices P^I, P^F, P^E, 85 and P^D. Train controlling devices P, as here shown, are of a well known type commonly used on subway lines of electric railroads and referred to as the tripper arm train stop. The position in which these devices affect a train is known as the tripping position, whereas the position in which they do not affect a train is known as the non-tripping position. Train-carried governing means with which such a train stop cooperates is well 90 known and forms no part of my present invention, and is therefore not shown in the drawings.

A signal, designated by the reference character S with a suitable distinguishing ex- 100

ponent, is placed adjacent points I, E, D, and A. As here shown, these signals are capable of displaying any one of three indications, namely, a clear proceed indication comprising a green light, a caution proceed indication comprising a yellow light, and a stop indication comprising a red light. Home relays for controlling these signals are designated by the reference character M with a suitable distinguishing exponent. A distant relay designated by the reference character J^E is shown for signal S^E, but the control of this relay being of a usual and well known form is omitted from the drawings. The lighting circuits are shown for signal S^E, but the lighting circuits for each of the other signals, being exactly similar to those for signal S^E, are omitted from the drawings.

A slow pick-up relay T at times causes 20 the operation of stop P^F to its non-tripping position when a train moves slowly enough through section F—H, whereas, in accordance with traffic conditions ahead, stop P^F is left in its tripping position if the train 25 moves at a higher rate of speed through section F—H. Section F—H, being provided solely for the control of relay T, will be referred to hereinafter as an auxiliary section, whereas all the other sections, having 30 as their function the control of stops P and signals S, will be referred to as main sections.

Having thus described, in general, the arrangement and location of the various constituent parts comprising my invention, I 35 will now proceed to explain the operation of the apparatus.

As shown in the drawings, all parts are in their normal condition, that is, the track sections are clear, the train stops are in their non-tripping position, and signals S are displaying the clear proceed indication.

With the track sections clear, current flowing along rail 1^a passes through the primary winding of each of the transformers 5, thereby causing each rectifier 6 to energize the respective auxiliary relay K. Relay K^H being energized, the circuit of relay T is open at contact 50 of relay K^H and relay T is therefore de-energized and its back contact 37—37^b is closed.

The stop P^I is energized by its operating circuit passing from wire x, through contact 32 of relay K^C, wire 33, contact 34 of relay K^E, 55 contact 35 of relay K^F, wire 36, contact 37—37^b of relay T, wire 41, contact 42 of relay K^H, wire 43, contact 44 of relay L^I, wire 47, and the operating mechanism of stop P^I to wire o. Stop P^F is energized by its operating circuit passing from wire x, through contact 18 of relay K^B, contact 19 of relay K^C, wire 20, contact 28 of relay K^E, contact 29 of relay K^F, wire 40, and operating mechanism of stop P^F to wire o. Stop P^E is energized by its operating circuit passing from

wire x, through contact 18 of relay K^B, contact 19 of relay K^C, wire 20, contact 21 of relay K^E, wires 22 and 25, and operating mechanism of stop P^E to wire o. Stop P^D is energized by its operating circuit passing from wire x, through contact 9 of relay L^A, contact 10 of relay K^B, contact 11 of relay K^C, wires 12 and 15, and operating mechanism of stop P^D to wire o.

At the same time, home relay M^I is energized by current flowing through the operating circuit traced for stop P^I as far as wire 43, thence through contact 48 of relay L^I, contact 49 of circuit controller a^I, and winding of relay M^I to wire o. Home relay M^E is energized by the circuit traced for stop P^E as far as wire 20, thence through contact 26 of relay K^E, contact 27 of circuit controller a^E, and winding of relay M^E to wire o. Relay M^D is energized by the circuit traced for stop P^D as far as contact 10 of relay K^B, thence through contact 16 of relay K^C, contact 17 of circuit controller a^D, and winding of relay M^D to wire o. The circuit by which green lamp G of signal S^E is lighted passes from wire x, through contact 52—52^a of relay M^E, contact 53—53^a of relay J^E, and lamp G to wire o.

I will now assume that with all parts in their normal condition as thus described, a train de-energizes relay L^X at station W, thereby closing a stick circuit for stop P^I passing from wire x, through contact 45 of relay L^X, contact 46 of circuit controller a^I, wire 47, and the operating mechanism of stop P^I to wire o. When the train enters section H—I, stop P^I will continue energized by its stick circuit until relay L^X again becomes energized as the train leaves the section immediately in the rear of signal S^I. On the other hand, when the train enters section H—I, relay M^I becomes de-energized due to the opening of contact 48 of relay L^I, thus causing the green light of signal S^I to be extinguished and the red light of signal S^I to be lighted by a circuit through a back contact of relay M^I, similar to that shown for the red light of signal S^E through contact 52—52^b of relay M^E. With the train in section H—I, relays K^E, K^F, and K^H continue energized, the current, flowing through transformers 5 for these relays, now passing through the axles of the train instead of through winding 7 of relay L^I.

When the train enters section F—H, relay K^H becomes de-energized since the current flowing down rails 1 and 1^a is now shunted between rails 1 and 1^a of section F—H by the axles of the train. Relays K^E and K^F, however, continue energized. As the train enters section E—F, relay K^F becomes de-energized in like manner as that described for relay K^H. As the train enters section D—E, relay K^E similarly becomes de-energized. Relays K^E, K^F, K^H, and L^I now continue de-energized until the train has passed out of section

D—E, whereupon all these relays become energized as before.

As the train approaches each of the stops P^F, P^E, and P^D, a stick circuit similar to that described for stop P^I, becomes closed for each of these stops in turn. The stick circuit thus closed for stop P^F passes from terminal α , through contact 30 of relay K^H, contact 31 of circuit controller a^F, wires 39 and 40, and the operating mechanism of stop P^F to wire σ . The stick circuit for stop P^E, becoming closed when relay K^F becomes de-energized, passes from wire α , through contact 23 of relay K^F, contact 24 of circuit controller a^E, wire 25, and operating mechanism of stop P^E to wire σ . The stick circuit for stop P^D, which becomes closed when relay K^E becomes de-energized, passes from wire α , through contact 13 of relay K^E, contact 14 of circuit controller a^D, wire 20, 15, and operating mechanism of stop P^D to wire σ . The stick circuits of stops P^F, P^E, and P^D being closed through back contacts of relays K^H, K^F, and K^E, all of which continue de-energized until the train passes out of section D—E, stops P^F, P^E, and P^D will all continue in their non-tripping position until the train passes out of section D—E, whereupon all three of these stops will be operated to their tripping position.

As the train has entered section D—E, the green light of signal S^E has been extinguished due to the de-energization of relay M^E by the opening of contact 26 of relay K^E, and the red lamp of signal S^E has then become lighted by its circuit passing from wire α , through contact 52—52^b of relay M^E, and lamp R to wire σ . As the train has entered section C—D, the green lamp of signal S^D has similarly been extinguished due to the de-energization of relay M^D by the opening of contact 16 of relay K^D, and red lamp R of signal S^D has become lighted by a circuit through a back contact of relay M^D.

When the train leaves section C—D, current flows from transformer 3 of section C—D along rails 1 and 1^a through transformer 5 at point C, across rails 1 and 1^a through the axles of the train, and back to transformer 3, causing relay K^C to become energized. The operating circuit of stop P^I now becomes closed through contact 32 of relay K^C, and stop P^I is then operated to its non-tripping position, whereupon the control circuit of relay M^I becomes closed through contact 49 of circuit controller a^I, causing the yellow lamp of signal S^I to be lighted by a circuit similar to that which will be described for the yellow lamp of signal S^E.

As the train leaves section B—C, relay K^B becomes energized, in addition to relay K^C, by current now flowing through the axles of the train across the rails of section A—B. The operating circuit for stop P^F is now closed through contact 18 of relay K^B, and stop P^F is then operated to its non-tripping position.

By the closing of contact 18 of relay K^B the operating circuit of stop P^F also becomes closed, and stop P^F is also operated to its non-tripping position, closing the circuit of relay M^F through contact 27 of circuit controller a^F. Relay M^F, upon opening its contact 52—52^b, extinguishes the red light of signal S^F and then, through its contact 52—52^a, completes the circuit for the yellow lamp of signal S^F which then becomes lighted by current passing from wire α , through contact 52—52^a of relay M^F, contact 53—53^b of relay J^F, and lamp Y to wire σ .

As the train moves out of section A—B, relay L^A becomes energized, in addition to relays K^B and K^C, thus completing, through its contact 9, the operating circuit of stop P^D which then moves to its non-tripping position. The circuit of relay M^D is then closed through contact 17 of circuit controller a^D, and relay M^D, then becoming energized, extinguishes the red light of signal S^D and causes the yellow lamp of signal S^D to become lighted.

I will now assume that while a train occupies section B—C, after having moved out of section C—D, a following train enters section F—H, de-energizing relay K^H and thereby completing the pick-up circuit of relay T, from wire α , through contact 50 of relay K^H, contact 51 of relay K^F, and winding of relay T to wire σ . If the train now proceeds slowly enough through section F—H, relay T will become energized before relay K^F becomes de-energized and opens contact 51. Relay T, upon becoming energized, closes a second operating circuit for stop P^F, passing from wire α , through contact 32 of relay K^C, wire 33, contact 34 of relay K^E, contact 35 of relay K^F, wire 36, contact 37—37^a of relay T, wires 38, 39, and 40, and operating mechanism of stop P^F to wire σ . Stop P^F thereupon becomes operated to its non-tripping position while the preceding train is still in section B—C.

I will now assume that, on the other hand, the following train, instead of moving slowly through section F—H, travels at such a speed that relay T does not close its front contact before relay K^F becomes de-energized. Stop P^F then continues in its tripping position, causing the application of the brakes of the following train.

From the foregoing description, it is clear that by the use of transformers 5 and auxiliary relays K the control of stops P and signals S is accomplished with only two instead of seven track circuits as commonly used between points I and A.

Although I have herein shown and described only one form of railway traffic controlling apparatus embodying my invention, it is understood that various changes and modifications may be made therein within the scope of the appended claims without depart-

ing from the spirit and scope of my invention.

Having thus described my invention, what I claim is:

- 5 1. A train controlling system, comprising a stretch of railway track divided into sections, a plurality of track circuits each including a track relay and a plurality of said track sections as well as a source of alternating current and for each junction between sections within said track circuit a transformer through the primary winding of which current flows from one section to the adjoining section at said junction, auxiliary control means respectively supplied with current by the secondary winding of each of said transformers, a plurality of trackway devices adjacent said stretch of track and arranged to co-operate with train carried governing means for at times controlling the movement of a train over said stretch of track, and means for controlling said device by said track relays and by said auxiliary control means.
- 10 2. A train controlling system, comprising a stretch of railway track divided into sections, a plurality of track circuits each including a track relay and a plurality of said track sections connected in series as well as a source of current and for each junction between sections within each track circuit an auxiliary control means energized by current from one section flowing into the adjoining section at said junction, a plurality of trackway devices adjacent said stretch of track and arranged to co-operate with train carried governing means for at times controlling the movement of a train over said stretch of track, and means for controlling said devices by said track relays and by said auxiliary control means.
- 15 3. A train stop system, comprising a stretch of railway track divided into sections, a plurality of track circuits each including a track relay and a plurality of said track sections connected in series as well as a source of current and for each junction between sections within each track circuit an auxiliary control means energized by current flowing from one section into the adjoining section at said junction, a plurality of tripper arm train stops adjacent said stretch of track and arranged to co-operate with train carried governing means for at times stopping a train, and means for controlling said train stops by said track relays and by said auxiliary control means.
- 20 4. A train controlling system, comprising a stretch of railway track divided into sections, a plurality of track circuits each including a track relay and a plurality of said track sections connected in series as well as a source of current and for each junction between sections within each track circuit an auxiliary control means energized by current from one section flowing into the adjoining section at said junction, a plurality of trackway devices adjacent said stretch of track and arranged to co-operate with train carried governing means for at times controlling the movement of a train over said stretch of track, and means for controlling said device by said track relays and by said auxiliary control means.
- 25 5. In a station-to-station train controlling system for governing the movement of traffic in one direction, comprising a stretch of railway track divided into sections including a first main section the entering end of which is adjacent the departure end of a station, an auxiliary section adjoining the leaving end of said first main section, a second main section adjoining the leaving end of said auxiliary section, a third main section adjoining the leaving end of said second main section, a fourth main section adjoining the leaving end of said third main section, a fifth main section the entering end of which is adjacent the arrival end of a second station and adjoins the leaving end of said fourth main section, a sixth main section the entering end of which adjoins the leaving end of said fifth main section and the leaving end of which is adjacent the departure end of said second station, a first, a second, a third, and a fourth trackway device adjacent the entering end of said first and second and third and fourth main sections, respectively, each said trackway device being arranged to co-operate with train carried governing means for at times controlling the movement of a train while said train is proceeding over said stretch of track, a first track circuit including said first and second and third main sections and said auxiliary section in series as well as a source supplying current to the leaving end of said third main section and a track relay connected across the rails at the entering end of said first main section and also including a first auxiliary control means energized by current flowing from said auxiliary to said first main section and a second auxiliary control means energized by current flowing from said second main section to said auxiliary section and a third auxiliary control means energized by current flowing from said third to said second main section, a second track circuit including said fourth and fifth and sixth main sections in series as well as a source supplying current to the entering end of said fourth main section and a second track relay connected across the rails at the leaving end of said sixth main section and also including a fourth auxiliary control means energized by current flowing from said fourth to said fifth main section and a fifth auxiliary control means energized by current flowing from said fifth to said sixth main section.

trol means energized by current flowing from said fifth to said sixth main section, a first, a second, a third, a fourth, and a fifth auxiliary relay controlled respectively by said first 5 and second and third and fourth and fifth auxiliary control means, a slow pick-up relay controlled by a back contact of said first auxiliary relay and a front contact of said second auxiliary relay, a pick-up circuit for 10 said first device controlled by a front contact of said first track relay and by a back contact of said slow pick-up relay as well as by a front contact of each of said first and second and third and fourth auxiliary relays, 15 a stick circuit for said first device controlled by a back contact of the track relay for a track circuit in the rear of said device, a first pick-up circuit for said second device controlled by a front contact of each of said 20 second and third and fourth and fifth auxiliary relays, a second pick-up circuit for said second device controlled by a front contact of each of said second and third and fourth auxiliary relays and said slow pick-up relay, 25 a stick circuit for said second device controlled by a back contact of said first auxiliary relay, a pick-up circuit for said third device controlled by a front contact of each of said third and fourth and fifth auxiliary 30 relays, a stick circuit for said third device controlled by a back contact of said second auxiliary relay, a pick-up circuit for said fourth device controlled by a front contact of each of said fourth and fifth auxiliary 35 relays and said second track relay, a stick circuit for said fourth device controlled by a back contact of said third auxiliary relay, a signal adjacent each of said first and third and fourth devices and capable of displaying 40 a "proceed" or a "stop" indication, a signal control relay for each of said signals, each of which signal control relays is controlled by a normally closed contact of the adjacent trackway device and by like contacts of the 45 same relays as control said adjacent device, and means for controlling each of said signals by the respective signal control relay.

6. In combination, a stretch of railway track comprising a first section, a second section adjoining said first section, a third section adjoining said second section, a track 50 circuit for said first section including a track relay, a track circuit for said second and third sections including said second and third sections in series and a second track relay connected to the rails of said third section as well as a source supplying current to the rails of said second section and an auxiliary control means energized by current supplied from 55 said second section to said third section, a signal for controlling traffic according to track conditions in said first and second sections, a second signal for controlling traffic according to track conditions in said second and third sections, means for controlling said 60

first signal by said first track relay and said auxiliary control means, and means for controlling said second signal by said second track relay.

7. In combination, a stretch of railway 70 track comprising a first section, a second section adjoining said first section, a third section adjoining said second section, a track circuit for said first section including a track relay, a track circuit for said second and third sections including said second and third sections in series and a second track relay connected to the rails of said third section as well as a source supplying current to the rails of said second section and an auxiliary control 80 means energized by current supplied from said second section to said third section, a trackway device for governing traffic according to track conditions in said first and second sections, a second trackway device for governing traffic according to track conditions in said second and third sections, means for controlling said first device by said first track relay and said auxiliary control means, and means for controlling said second device by 85 said second track relay.

8. In combination, a stretch of railway track comprising a first section, a second section adjoining said first section, a third section adjoining said second section, a track 90 circuit for said first section including a track relay, a track circuit for said second and third sections including said second and third sections in series and a second track relay connected to the rails of said third section as well as a source supplying current to the rails of said second section and an auxiliary control means energized by current supplied from said second section to said third section, a tripper arm train stop for operating train-carried governing means according to track 95 conditions in said first and second sections, a second tripper arm train stop for operating train-carried governing means according to track conditions in said second and third sections, means for controlling said first train stop by said first track relay and said auxiliary control means, and means for controlling said second train stop by said second track 100 relay.

In testimony whereof I affix my signature.
HOWARD A. THOMPSON.
